UNITED STATES PATENT OFFICE

ARTHUR EDWARD HOUGHTON, OF EAST TWICKENHAM, ENGLAND

MEANS FOR SUPPORTING ARTICLES ON WEARING APPAREL

Application filed September 28, 1931, Serial No. 565,671, and in Great Britain October 8, 1930.

This invention relates to means for supporting on wearing apparel, pencils or fountain pens or any other desired article provided with a pocket clip similar to the well known type used on fountain pens.

It has been found in practice that such clips—by being continually removed and replaced—wear away the edge or seaming of the pocket on which they are fixed, and on account of the various thicknesses of the material of the wearing apparel the clips are not always securely clipped, so that when the wearer stoops or bends forwards and downwards, he loses the pen or other article supported by the clip.

The present invention consists of a device for supporting fountain pens, pencils or other articles within a pocket of wearing apparel from a clip provided on the article, consisting of a clip supporting strip or supporter made of material sufficiently rigid to receive and hold the clip and adapted to be permanently or detachably fastened at each end within the upper portion of the pocket.

The supporting strip may be held at each end in the pocket by spring clips such as those used heretofore for holding pens and pencils in the waistcoat pocket.

The device may be made of a sheet or strip of material of a fairly stiff yet resilient nature and consisting of one or more thicknesses, and such sheet is provided with means for fixing it within the top portion of the pocket of the wearing apparel, such strip being made of a material that will yield laterally when the clip is forced over it, and still be of sufficient resiliency to retain the clip to which the pen, pencil or other article is affixed.

The strip or supporter may be provided with any suitable means for securing it in the pocket, such as a spring clip at each end to engage the edge of the pocket in the manner of an ordinary clip, or one or more safety pins or snap-on fasteners, such securing means being so arranged that they can be readily attached to the wearing apparel inside the pocket, or inside a belt or band, or the strip may be permanently fixed in position in the pocket.

The strip or supporter may be formed by folding or other method, at the top of the sheet of resilient material adapted to fit inside the opening of the pocket, and such strip may contain a thin flexible strip of thin metal, whalebone or other suitable flexible material so as to give the necessary rigidity to the strip when the material of the strip is not in itself sufficiently rigid. The thin flexible strip may be in the form of a flattened or oval spiral spring or split tube.

Various methods of carrying out the invention are illustrated by the accompanying drawing wherein Figure 1 is a general view of the device in use as a fountain pen supporter applied to a waistcoat pocket, Figure 2 is a side elevation and Figure 3 a front elevation of a method of constructing the device.

In the drawing *a* is the main portion of the strip or supporter, *b* are spring clips fixed at each end of the supporter *a* and adapted to clip the upper edge *e* of the pocket opening and so hold the supporter inside the pocket while extending freely the full width thereof and so leave free spaces in the pocket at the front and back of the supporter. When in use to support pens the body of the pen is inserted into the pocket down the back of the supporting strip *a* and the pen clips *c* forced over the front of the supporting strip and between it and the inside of the front portion of the pocket, so that the pen clip will not be wholly visible as at present used.

The device as illustrated in Figures 2 and 3 consists of two spring clips *b* adapted to grip the top edge of the pocket and having front hook like portions adapted to extend down the front of the top edge of the pocket. The back members *b* of these clips are fixed at the opposite ends of a flattened spiral spring *d* made of strip material and of which the ends are secured to the back members *b* by passing through holes *b* and the end *b* bent over. The ends of the spiral spring *d* may be secured to the back members *b* by riveting or any other suitable manner.

This device may be made entirely of spring metal, or such metal may be provided with covering material *c* of leather or any other

suitable fabric or combination of fabrics the edges being sewn or otherwise secured together. The spiral spring *d* or any substitute therefor may be made in one with the clips 5 *b1, b2.*

It is well known that owing to the differences in thickness of material from which clothes are made, such as winter and summer material, the ordinary clip will not retain 10 its grip when changing from thick to thin clothes, and the article is liable to be lost as indicated above, whereas with the present device the strip itself being transferred from one garment to another the grip is constant, 15 and the loss of the pin or article prevented.

What I claim and desire to secure by Letters Patent is:—

1. A device for supporting fountain pens, pencils and other articles within a pocket of 20 the users' apparel from a spring clip provided on the article, comprising a single laterally resilient substantially rigid supporting strip, means for holding it at each end only within the edge of the pocket, the supporting strip 25 being sufficiently rigid and thick at its upper portion as to enable the clip of the article to be sprung over it independently of and within the front edge of the pocket, and so that the clip of the article as well as the body thereof 30 will be within and not extend over the front of the pocket.

2. A device for supporting fountain pens, pencils and other articles within a pocket of 35 the users' apparel from a spring clip provided on the article, comprising a single laterally resilient substantially rigid supporting strip, a clip at each end of the strip for supporting it at each extreme and within the upper portion of the pocket, the supporting strip being 40 sufficiently rigid and thick at its upper portion as to enable the clip of the article to be sprung over it independently of and within the front edge of the pocket, and so that the clip of the article as well as the body thereof 45 will be within and not extend over the front of the pocket.

3. A device for supporting fountain pens, pencils and other articles within a pocket of 50 the users' apparel from a spring clip provided on the article, comprising a single laterally resilient substantially rigid supporting strip and two spring clips one fixed at each end of the upper edge of the strip, the two spring 55 clips being made to engage the opposite ends of the top edge of the pocket while suspending the supporting strip within the pocket, the strip being sufficiently rigid and thick at its upper portion as to enable the clip of the article to be sprung over it independently of 60 the front edge of the pocket, and so that the clip of the article as well as the body thereof will be within and not extend over the front of the pocket.

4. A device for supporting fountain pens, 65 pencils, and other articles within a pocket of

the users' apparel from a spring clip provided on the article, comprising a sheet of fabric, a single laterally resilient stiffening strip for the upper edge of the sheet of fabric, and means for holding the sheet of fabric at its 70 edges within the pocket, the strip being secured to the upper edge of the fabric and to form therewith a thickened portion to enable the clip of the article to be sprung over it independently of the front edge of the pocket, 75 and so that the clip of the article as well as the body thereof will be within and not extend over the front of the pocket.

5. A device for supporting fountain pens, pencils and other articles within a pocket of 80 the users' wearing apparel from a spring clip provided on the article, comprising a sheet of fabric, a stiffening strip for the upper edge of the sheet of fabric, and two spring clips fixed at each end of the upper edge of the 85 strip, the two spring clips being fixed respectively at the opposite ends of the strip, and made to engage the opposite ends of the top edge of the pocket while suspending the supporting strip within the pocket, the strip being secured to the upper edge of the fabric and to form therewith a thickened portion to enable the clip of the article to be sprung over it independently of the front edge of the pocket, and so that the clip of the article as 95 well as the body thereof will be within and not extend over the front of the pocket.

6. A device for supporting fountain pens, pencils and other articles within a pocket of 100 the users' apparel from a spring clip provided on the article, comprising a sheet of fabric, a flattened spiral spring for the upper edge of the sheet of fabric, and means for holding the sheet of fabric at its edges within the pocket, the flattened spiral spring being secured to 105 the upper edge of the fabric and to form therewith a thickened portion to enable the clip of the article to be sprung over it independently of the front edge of the pocket, and so that the clip of the article as well as the 110 body thereof will be within and not extend over the front of the pocket.

7. A device for supporting fountain pens, pencils and other articles within a pocket of 115 the users' apparel from a spring clip provided on the article, comprising a flattened spiral spring and means for holding its ends within the pocket, the flattened spiral spring forming a thickened strip to enable the clip of the article to be sprung over it independently of the front edge of the pocket, and so that the clip of the article as well as the body thereof will be within and not extend over the front of the pocket.

In testimony whereof, I affix my signature. 125
ARTHUR EDWARD HOUGHTON.
